US00D883373S

(12) **United States Design Patent** (10) Patent No.: **US D883,373 S**
Sorio (45) Date of Patent: **** May 5, 2020**

(54) **PAYMENT DEVICE**(71) Applicant: **Custom S.p.A.**, Fontevivo (Parma) (IT)(72) Inventor: **Adriano Sorio**, Fontevivo (IT)(73) Assignee: **CUSTOM S.P.A.**, Fontevivo (Parma) (IT)(**) Term: **15 Years**(21) Appl. No.: **29/658,930**(22) Filed: **Aug. 3, 2018**(30) **Foreign Application Priority Data**

Feb. 13, 2018 (EM) 004706752-0002

(51) LOC (12) Cl. **18-01**

(52) U.S. Cl.

USPC ..... **D18/4.4; D14/336**(58) **Field of Classification Search**

(74) Attorney, Agent, or Firm — Wenderoth, Lind & Ponack, L.L.P.

(57) **CLAIM**

The ornamental design for a payment device, as shown and described.

DESCRIPTION

FIG. 1 is a perspective view of the invention;

FIG. 2 is a front view of the invention;

FIG. 3 is a rear view of the invention;

FIG. 4 is a right side view of the invention;

FIG. 5 is a left side view of the invention;

FIG. 6 is a top view of the invention; and,

FIG. 7 is a bottom view of the invention.

1 Claim, 7 Drawing Sheets(56)
